UNITED STATES PATENT OFFICE.

MAXIMILIAN ANGST, OF NEUHAUSEN, SWITZERLAND, ASSIGNOR TO ALUMINUM-INDUSTRIE-AKTIEN-GESELLSCHAFT, OF NEUHAUSEN, SWITZERLAND, A SWISS CORPORATION.

ADJUSTABLE CHILL MOLD.

Application filed December 21, 1923. Serial No. 682,129.

To all whom it may concern:

Be it known that I, MAXIMILIAN ANGST, a citizen of the Swiss Confederation, and residing at Neuhausen, Switzerland, have invented certain new and useful Improvements in Adjustable Chill Molds, of which the following is a specification.

This invention relates to adjustable molds for use in the manufacture of ingots of aluminium and its alloys which can be rolled.

In the gold and silver industry it is known to provide adjustable molds having one fixed longitudinal wall and a second longitudinal wall movable along the fixed one. These molds have the defect, however, that they enable only ingots of various breadth, and not ingots of various thickness to be cast. In addition, these known molds are intended for ingots of only quite small dimensions and are not adapted for use in casting aluminium at the present day as ingots of 40-1000 kg. are now required.

Such aluminium ingots weighing up to 100 kg. are usually cast so that they stand on edge in the chill molds, so that the so-called pouring piece is on the smallest face of the cast ingot. When perfect ingots of heavier weight are to be produced they are cast in chill molds that lie down flat and the pouring piece is on one of the larger faces of the ingot so that when the ingot is rolled it is situated on the middle of the rolled plate or sheet. As this is not permissible the pouring piece has to be removed by milling, turning or planing and a flat face produced.

In the improved mold according to the present invention the movable longitudinal wall can be shifted horizontally towards and away from the fixed one, and in addition the mold comprises movable end walls, so that it enables ingots to be cast edgewise-on up to largest sizes and weights required. The movable longitudinal wall preferably rests with a cranked portion on the bottom of the mold, whereby not only is a tight fit and a considerable degree of movability afforded, but also sufficient stability of the movable longitudinal wall in each position it may occupy.

The metal is poured along a narrow side into the chill mold and the pouring piece is formed on a narrow side of each ingot, one or more pouring pieces being produced according to the length of an ingot. The

pouring pieces on the narrow side have the great advantage that they do not need to be removed before the rolling operation, because they pass into the edges which are removed in any case when cutting the plates or sheets. Considerable loss of material is saved and extra work is avoided, and the production cost of the ingots or billets ready for rolling is diminished. Owing to dispensing with the pouring-in funnel material is also saved. Tests have shown that an important advantage of the improved cast-iron mold is that the ingot poured broad-side-on can be made much denser and completely free from pores, so that it is preferred for the manufacture of plates or sheets free from blisters.

Further, the adjustability of the walls of the mold has the great economic advantage that a smaller number of molds suffices to meet the very various demands of the rolling mill, whereas heretofore for each shape or size of ingot a mold had to be made especially for it.

One form of improved chill mold according to the invention is illustrated by way of example in the accompanying drawing, wherein:

Figure 1 is a top plan view,

Figure 2 is a vertical longitudinal section, and

Figure 3 is a transverse section.

Like reference numerals designate like parts throughout the several views.

The mold comprises a fixed longitudinal wall 2 integral with the bottom 0, and a movable longitudinal wall 1 movable towards and away from the wall 2. This wall 1 has a cranked portion with which it rests on the top of the bottom 0 of the mold, and the whole mold is mounted in a pouring frame which is not illustrated.

The two end walls 3 and 4 are movable in the longitudinal direction of the mold. The two longitudinal walls 1 and 2 can be drawn together by bolts 5 which are pivoted to the wall 2 and extend through slots in the wall 1 to the outside of the latter where they carry nuts. Further, the wall 1 can be shifted by screw bolts 6 towards and away from the bottom, packing of various thickness according to the desired thickness of ingot being employed between the offset limb of the wall 1 and the opposed vertical face of the bottom 0 of the mold. The end walls 3

and 4 can be given the desired width corresponding to the required thickness of ingot by means of packing pieces, or alternatively each end wall may be exchanged for another one of the desired size.

In order to prevent the upper parts of the longitudinal walls 1, 2 from bulging outwards during the pouring of the metal they may be held together, by one or more **U**-shaped members, the number employed depending on the length of the mold.

Bolts 7 extending through the offset limb of the wall 1 and abutting against the opposed vertical face of the bottom 0 of the mold serve for forcing the wall 1 away from the ingot so that the latter may be removed from the mold. It has been found in practice that it suffices to shift the wall 1 about 1-2 mm. in order to enable the ingot to be conveniently drawn out of the mold after removal of the end wall 4 and tilting the mold.

The construction of the described chill mold is such that the ingot can be taken out in the shortest time possible and that the mold can be prepared exceedingly rapidly for a new pour.

I claim:

1. An adjustable mold for casting ingots of aluminium and its alloys, comprising in combination a bottom, a longitudinal wall fixed thereon, an adjustably movable longitudinal wall making joint with the bottom and movable towards and away from the fixed wall, and two end walls making joint

each with the bottom and with the longitudinal walls one of which end walls is movable towards and away from the other, substantially as described.

2. An adjustable chill mold for casting ingots of aluminium and its alloys, comprising in combination a bottom, a longitudinal wall fixedly mounted thereon, a movable longitudinal wall having an offset lower portion seated on the bottom, and movable towards and away from the fixed wall, two end walls making joint each with the bottom and with the two longitudinal walls and slideable each towards and away from the other along the bottom, means for shifting the movable longitudinal wall towards the fixed longitudinal wall, and means for shifting the movable longitudinal wall substantially as described.

3. An adjustable mold for casting ingots of aluminium and its alloys, comprising in combination a bottom and a fixed longitudinal wall integral therewith, a movable longitudinal wall having an offset lower portion seated on the bottom and movable thereon towards and away from the said fixed wall, and two end walls making joint each with the bottom and with said longitudinal walls, one of which end walls is movable on the bottom towards and away from the other end wall substantially as described.

In testimony whereof, I affix my signature.

MAXIMILIAN ANGST.
